UNITED STATES PATENT OFFICE

2,554,231

ELECTRIC FURNACE

Thomas M. Wymore, Lincoln, Nebr.

Application August 4, 1949, Serial No. 108,579

2 Claims. (Cl. 219—39)

1

This invention relates to hot air furnaces and more particularly, it is an object of this invention to provide an improved electrical furnace.

Another object is to provide a heater which can be easily attached to hot air ducts of the type used in homes.

Another object of the invention is to provide a hot air furnace which requires a minimum of supervision.

Another object is to provide separate heating elements within a furnace as described, any one of which may be easily removed for inspection, replacement or repair.

A still further object resides in the provision of an air heater which gives more even heating thermostatically, avoiding sudden and extreme changes of temperature.

Yet another object of the invention is to provide a device for the purpose described which is sturdy and durable in construction, reliable and efficient in operation, and relatively simple and inexpensive to manufacture, assemble and utilize.

Other and still further objects and advantages of the invention will become apparent from the following detailed description of a preferred embodiment thereof.

In the drawing:

Figure 1 is a side elevation of the new electrical air heater, a portion of the outer casing being shown broken away for purposes of illustration.

Figure 2 is a view in section taken substantially on the line 2—2 of Figure 1.

Figure 3 is a front elevation of one of the resistance coils of the furnace and the supporting grid therefor.

Figure 4 is a side elevation of the heating element and grid shown in Figure 3.

Referring now to the drawing for a more particular description and first to Figure 1, 10 indicates an air duct to which the heating element housing of this invention is secured, as indicated at 12.

The housing 12 is provided with a floor plate 14 which is of rectangular shape and is provided with one or more air admittance apertures 15 therethrough. The apertures 15 are positioned immediately inward from the outer edges of the floor plate.

The rectangular housing 12 is outwardly flared at its upper end as shown at 16 where the housing joins the duct 10.

The housing 12 is secured to the duct 10 and is disposed in communication therewith at the open upper end of the housing.

2

A heating block 22 is provided and has a plurality of flat, parallel equidistantly spaced apart slots 30 therein and extending upwardly from the bottom thereof. The block 22 is preferably formed of aluminum and rests upon the floor plate 14.

The upper side edges 26 of the block 22 are preferably curved for permitting air to rise upwardly from the sides of the block 22 in operation and as indicated by the arrows 30'. A plurality of like frames or grids 32 are provided as best seen in Figures 3 and 4; each grid 32 preferably includes a plurality of parallel interconnected portions 34 around which latter a resistance wire 36 is wound to form resistance elements for insertion into the slots 30 of the block 22.

The resistance wire 36 of each heating element is disposed with its ends connected to terminal posts 38 adjacent the bottom of the grid 32. A lead-in cable portion 40 is disposed attached to each heating element, each portion 40 having two wires 42 secured, one each, to the posts 38.

The portions 40 are connected to a terminal box 44 and a lead-in wire 50 is also disposed entering the terminal box 44, the arrangement of wires in the box 44 being such as to conduct electricity from the wire 50 to the wires 40.

The wire 50 can be secured by any suitable means to an electrical circuit.

The elements are each disposed through a separate opening 60 in the bottom wall or base 14. The openings 60 are disposed in use beneath the slots 30.

The grids 32 are each provided with a pair of spring clips 70 disposed one clip on each side of the bottom end of each grid. The clips 70 are inclined outwardly at their free upper ends in a manner whereby they tend to hold the grids 32 in position in the opening 60 once the grids 32 are inserted through the opening 60.

The housing 12 can be provided with inwardly curved upper end portions 90 adjacent the duct 10 and on the elongated side walls 92 thereof for conducting heat upwardly to the duct 10 from the side of the block 22, as indicated by the arrow 100 in Figure 2.

In operation, the elements will become heated, heating the block 22 and causing cold air to flow upwardly from the block 22, partly in the directions of the arrows 30' and 100.

The air is then carried by the duct 10 to the rooms of the dwelling in a usual manner.

At times when a thermostat, not shown, is used to turn the electricity on and off, it will be seen that there will be no sharp rises and chilling drops in temperature because of the

time required for the block 22 to lose its stored heat. An even heating is thus insured.

From the foregoing description it is thought to be obvious that an electric furnace constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

I claim:

1. In an electric heater, the combination which comprises a horizontally disposed base having openings therethrough, a heat transferring block having parallel spaced slots extended upwardly therein from the lower surface mounted on said base, a housing mounted on the base and having side walls extended upwardly from the edges of the base with the said side walls spaced from the said heat transferring block, an air circulating duct extended through the upper end of the housing with the ends thereof extended from the ends of the housing providing connections to heating ducts leading from the heater, and independently mounted electric heating elements 30 extended upwardly through the openings in the intermediate part of the base and into the slots of the heat transferring block whereby the elements are independently replaceable.

2. In an electric heater, the combination which 35

comprises a rectangular-shape heat transferring block having arcuate upper edges and having spaced transversely disposed slots extended upwardly therein from the lower end thereof, a horizontally disposed base having slots therein corresponding with the slots of the heat transferring block and having edges with openings therethrough extended beyond the sides and ends of the block, a housing having side and end walls 10 spaced from the sides and ends of the block, respectively, extended upwardly providing a housing around the block and the said sides having arcuate upper edges spaced from and corresponding with the said arcuate upper edges of the block, a longitudinally positioned duct extended through the upper part of the housing, and a plurality of grids having heating elements carried thereon extended upwardly through the slots of the base and into the slots of the said 20 heat transferring block.

THOMAS M. WYMORE.
